NURSERY LAMP

Larry D. Reser, R.R. 2, Rossville Township,
Shawnee County, Kans.

Filed July 13, 1964, Ser. No. 80,837

Term of patent 14 years

(Cl. D48—20)

FIG. 1

The essential features of the design reside in the full line portions of the drawing.

I claim:

The ornamental design for a nursery lamp, substantially as shown and described.
